CLAIM

The ornamental design for a step light as shown and described.

DESCRIPTION

FIG. 1 is a front, right and top perspective view of a step light showing my new design;

FIG. 2 is a rear, left and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof; and,

FIG. 9 is an enlarged view of a portion labeled as "9" on FIG. 1.

The long dash-short dash broken lines depict enlargement boundaries that form no part of the claim. The evenly broken lines illustrate portions of the step light that form no part of the claimed design.
